UNITED STATES PATENT OFFICE.

DONALD FRASER, OF MILWAUKEE, WISCONSIN, ASSIGNOR TO CHAIN BELT COMPANY, OF MILWAUKEE, WISCONSIN, A CORPORATION OF WISCONSIN.

LOADER FOR CONCRETE-MIXERS AND SIMILAR MACHINES.

1,109,915.

Specification of Letters Patent.

Patented Sept. 8, 1914.

Application filed November 18, 1912. Serial No. 732,110.

To all whom it may concern:

Be it known that I, DONALD FRASER, a citizen of the United States, residing at Milwaukee, in the county of Milwaukee and 5 State of Wisconsin, have invented certain new and useful Improvements in Loaders for Concrete-Mixers and Similar Machines, of which the following is a specification.

My invention relates to loading devices 10 such as are commonly employed for delivering material to concrete mixers; and it has for its object to improve the construction of the same, and adapt them for the various uses to which loaders of this kind are put.

15 In the accompanying drawings—Figure 1 is a side elevation of the invention as applied to a concrete mixer, the outer end of the loader being open. Fig. 2 is a top plan view of the loader detached. Fig. 3 is a 20 side elevation of the loader detached, its outer end being closed.

In such drawings, 2 designates the revolving drum of a concrete mixing machine, it being formed with an axial feed opening 3. 25 4 designates the loader, which is represented as being pivotally connected, at 5, with a framework 6 surrounding the drum. The loader is provided with a pivoted bail 7, the cross-bar of which carries a sheave 8 around 30 which passes the cable 9 by means of which the movements of the loader are controlled.

The parts thus far described in their general features and relationship are well known in the art and may be widely varied 35 without departing from the essential features of my invention.

The loader 4 is formed with an open spout 10 through which the materials placed therein are delivered into the drum, through the feed opening 3, the delivery being effected 40 by tilting the loader. It is of such shape and so proportioned to the other parts of the apparatus that when in its lowermost position, as represented in Fig. 1, it rests upon the ground or other surface on which the mixer is supported. The outer end of the loader, that is, the one distant from the spout 10, is preferably shaped to have a flat bottom 11, so as to afford a broad supporting base, while the loader is being filled. 45 This portion of the loader is closed by an end wall 12 which is pivotally connected, as by hinges 15, with the front or outer edge of the bottom 11. The side walls 13 of the 50 loader terminate on lines which are prefer-

ably perpendicular to the plane of the flat bottom 11 and against the end edges of such walls the end wall or gate 12 rests when in position to close the end of the loader, the wall then being vertically disposed. Secured to the end wall at its ends are segmental shaped side pieces 14 which are adapted to lie just inside of the side walls 13, when the gate or end piece 12 is turned up to close the loader, and which practically form extensions of the said side walls when the end wall is let down to open the loader, as indicated in full lines in Fig. 1. I provide means for holding the end wall in position to close the loader, such means being of any usual or preferred construction. As represented they consist of a pair of brackets at each side of the loader, one, 16, of each pair being carried by the pivoted end wall, and the other, 17, by the main portion of 75 the loader. These brackets come together when the end wall is turned up to close the loader and a bolt 18 holds the parts together.

The arrangement described is advantageous in several particulars. When the loader is being filled, for instance from wheel barrows that are being moved over the surface on which the mixer and the loader rest, the end wall may be let down as indicated 80 in full lines in Fig. 1, permitting the barrows to be wheeled directly into the loader and dumped. Then when sufficient material has been delivered the end wall may be closed and the loader tilted to deliver. Under other circumstances it may better suit 85 to have the rear end of the loader closed while being filled, in which event the end wall may be raised and secured in closing position. 90

What I claim is:—

1. A tilting loader having an open delivery end portion, a bottom adapted to rest upon a support, permanent side walls bounding the said delivery end portion and the bottom of the loader, and a hinged wall for the outer end of the loader adapted to be moved into substantially the plane of the bottom, whereby the loader is open at both ends, or to be turned up into engagement with the ends of the sides to form a closing wall for the outer end of the loader. 100

2. A tilting loader having an open delivery end and an open outer end, a bottom, a portion of which is adapted to rest upon 105

a support, permanent side walls, a pivoted end wall connected at its lower edge with the outer end of the bottom, and side pieces carried by the end walls, these parts being arranged as described whereby when the end wall is let down the loader is open from end to end and the side pieces carried by the hinged end wall form practical continuations of the side walls of the loader, and when said end wall is turned up it closes the outer end of the loader.

3. A pivoted tilting loader having an open spout section to which is secured the pivot about which the loader turns, an outer portion open at its end and having a bottom adapted to rest upon a support, there being permanent side walls bounding both said sections of the loader and terminating

on lines which are substantially perpendicular to the plane of the resting portion 20 of the bottom, and an end wall hinged to the outer edge of the bottom of the loader and provided with segmental side pieces arranged to lie close to and parallel with the side walls, whereby when the end wall is 25 let down it forms a practical continuation of the bottom of the loader, and the segmental side pieces which it carries practical continuations of the side walls, and when turned up meets the vertical edges of the 30 side walls and closes the outer end of the loader.

DONALD FRASER.
